UNITED STATES PATENT OFFICE

JESSE A. B. SMITH, OF STAMFORD, CONNECTICUT, ASSIGNOR TO UNDERWOOD ELLIOTT
FISHER COMPANY, OF NEW YORK, N. Y., A CORPORATION OF DELAWARE

TYPEWRITING MACHINE

Application filed June 23, 1925. Serial No. 38,958.

This invention relates generally to improvements in web-manifolding machines of the character disclosed in the Wernery & Smith Patent No. 1,132,055, dated March 16, 5 1915. It relates more particularly to the method and means for simultaneously producing separate typed forms and a record-web typed with the same data as the forms, which is directly accessible at all points along 10 its length to expose said data, the means to this result including among other devices a novel guide for the record-web so arranged as to cause the refolding of said record-web into a book or folded stack subsequently to 15 the typing operation.

In practicing my invention, a multiple-ply web, having successive printed bill-forms, is fed with interleaved carbon-sheets around the platen. The work-web is cross-folded 20 back and forth, so as to form a pack, and is usually led from a bin at the back of the machine and upwardly over the rear end of the usual carriage-extension, whence it passes forwardly to and around the platen and upwardly at its front, under a knife, and up over the delivery table.

There is provided a cross-folded record-web which is fed into the machine with the main work-web. This record-web may be a 25 separate ply or may be the top ply of the main work-web severed from the latter by a knife in the rear of the platen, and, instead of feeding upwardly in front of the delivery table with the other work-web, is conducted 30 behind said table, and then led rearwardly 35 over said rear carriage-extension. In some cases, the record-web is caused to feed downwardly from the rear end of said extension to a refolding receptacle, the latter being positioned with respect to said rear end so that 40 said web-ply is automatically refolded back and forth into it by gravity, forming a new pack.

The transverse folds in the record-web are 45 sometimes spaced two or three bill-lengths apart. In such case, to prevent the entering portion of the main work-web from colliding or interfering with the refolding portion of the record-ply, it is a feature of my 50 invention to provide a guide-member posi-

tioned to the rear of said rear extension and supported thereon for controlling the refolding of the record-ply to keep the latter from striking against the main work-web as the record-ply swings back and forth in being refolded. This construction also prevents the refolding record-ply from binding on the main work-web where the latter passes over the rear end of said extension. The 55 typed whole record-web dangles from the traveling carriage of the typewriter, the dangling portion being sufficiently long to permit it to sway with the carriage at its upper portion while its lower portion lies still in the refolding receptacle, and without 60 danger of fouling or wrinkling said web. 65

In typing the fan-folded web, the record-sheet, that is to say, the ply nearest the platen, is slit from the other plies by means of a knife mounted upon the carbon-carrier. The separated record-ply is passed 70 behind the delivery table, the other plies of the web being led over the front of said table in the regular manner. The record-ply is then held at the rear of the table by 75 means of a clamp, which may be controlled simultaneously with the releasing of the platen-frame preparatory to straightening out the web to strip the carbons therefrom.

The usual heading is not necessary on the 80 record-web, which may have only spaces corresponding to the item-sections of the statement-sheet-web, thus making the record-web spaces relatively short, and consequently necessitating successive readjustments between 85 the statement-sheet-web and the record-sheet for the various statements typed. To facilitate positioning of the record-sheet after the last entry has been typed, the record-sheet may extend slightly beyond one edge of the statement-sheet, and the record-sheet may be provided at its side edge with indices to indicate the top edge of each succeeding section of the record-sheet. 90

Other features and advantages will hereinafter appear. 95

In the accompanying drawings, Figure 1 is a side view in elevation of an Underwood fan-fold typewriting machine, 100

as applied to the handling of work which forms the subject of this invention.

Figure 2 is a perspective view of the record-web guiding member which is attached to the rear extension of the machine as a sub-extension thereof.

Figure 3 is a side view in elevation of the platen of the machine, showing the work-web in front of the table in typing position, 10 the record-web being shown behind the table in cooperating position with a binding clamp.

Figure 4 is a perspective view of the fan-folded and cross-folded web having identifying numerals printed thereon.

15 Figure 5 is a plan view of the carbon-carrier, showing the slitting knife for separating the record-ply of the web from its associated statement-plies.

Figure 6 is a diagrammatic side view in 20 elevation showing the gaging position of the web.

Figure 7 is a diagrammatic side view in elevation showing the straightened web in the carbon-stripping operation.

25 Figure 8 is a modified form of the invention, in which, for the purpose of economizing paper, and to further condense the record-web, the same is fed to the machine from a separated container, the lengths of the 30 cross-folds of the web corresponding to the length of the typed portion of the forms.

Figures 9 and 10 are perspective views, respectively, of the fan-folded statement-web and the cross-folded record-web, both being correspondingly numbered.

Figure 11 is a diagrammatic side view in elevation, showing the typing position of the statement-web and associated record-web in the modified form.

40 Figure 12 is a view similar to Figure 11, showing the position of the statement-web and associated record-web previous to the straightening-out operation.

Figure 13 is a view also similar to Figure 45 11, showing the statement-web in its gaging position.

Figure 14 shows the tearing-off position of the statement-web, the platen being in its feeding position.

50 Figure 15 is a perspective view of the platen, showing the statement-web and the record-web corresponding to the position of the statement-web and the record-web illustrated in Figure 11.

55 Figure 16 is a perspective view of the platen, showing the statement-web and the record-web corresponding to the position of the statement-web and record-web illustrated in Figure 12.

60 In Figure 1, an Underwood fan-fold type-writing machine 10 is shown placed upon a table 10^a. An assembled fan-folded and cross-folded web 11 is drawn up from a receptacle or box 12 at the rear of the machine.

65 The web is passed over a cross-bar 13 on the

rear of the usual carriage-extension 13^a, and is then threaded between carbon-blades 14 having carbons 15 fast thereto, the ends of the web being then matched with the ends of the carbons preparatory to inserting the assembled pack at the rear of a platen 17 down a rear table 16 and forwardly under the platen 17 co-operating with associated feed-rolls 18, and, by rotating the platen, the web is fed up in front thereof past the printing point, which is indicated in Figure 3 by a type-bar 18^a.

70 In order that the upper ply of the web, that is to say, the ply nearest the platen may be used as a separate continuous record-web, there is provided a slitting knife 19, which may be secured to the carbon-carrier 20, as shown in Figure 5. The knife presents a

beveled cutting edge 21 to the border of the web, and is interleaved between the upper 80 ply and the next ply in a manner to separate the plies as the carbons are moved relatively to the web. It can be seen that for the purpose of the invention, the record-web may be

85 a separate ply or web cross-folded with the state-ment-web to form a single transversely-fan-folded work-web. Thus, the fan-folded web and the record-web 22 are fed around the platen in a separated condition, so that, on being delivered at the top of the platen past 90

the printing point, the record-web may be led behind a table 23 and over a clamping member 24 which co-operates with the table to 95

clamp the record-web. The other plies of the assembled web are passed over the table 100

in the regular manner in the direction of a gage 25 adjustably mounted upon an extension 26 on the table 23 by means of a thumb screw 27.

After completion of typing upon the form, 105 the platen is rotated by means of a finger-piece 28, and the work-web is run up to the gage 25, as shown in Figure 6, whereupon a

latch 29, normally holding the platen in registration with the feed-rolls, is released by 110 disengaging a co-operating pin 30, and simultaneously the clamping member 24 is rendered effective to grip the record-web against the table. The platen is then swung up-

wardly on a rock-shaft 31, to a position 115 shown in Figure 7 to straighten out the web, which is held against the gage 25 while the carbon-carrier is pushed backwardly to present the carbons to a fresh portion of the web. As the carbon-carrier is moved to dis-

place the carbons, the record-web is separated 120 from its associated plies by means of the slitting knife.

The platen is again lowered to co-operating 125 position with the feed-rolls and the clamping member 24 is forcibly released against a closing spring 32 by the action of the latch 29 striking a lug 33. The clamping member 24 usually includes side arms 34 rockably mounted upon a fixed pivot 35. After lock-

ing the platen in its normal position, thereby releasing the record-web, the typed forms are torn off against a knife 48 at the delivery side of the platen.

The record-ply is delivered past the bar 13 at the rear end of the extension 13^a to permit it to descend by gravity. To prevent the ascending or entering portion of the work-web 11 from coming into collision with the descending record-ply as certain folds of the later swing forwardly about fold-lines 37 to lie flat in a receptacle 36, there is provided a refolding or guiding bar device 38 for the record-ply 22. Said refolding bar may consist of a bent wire having side arms 39 designed to straddle the entering web and a cross-piece 40, the arms being bent at the ends thereof, forming lower concave hooks 41 for engaging a cross-bar 13^b disposed a short distance below the cross-bar 13, and upper convex hooks or bends 41^a to engage around the cross-bar 13.

The cross-piece 40 will preferably be positioned in the rear of the cross-bar 13 a distance 25 equal to or greater than the lengths of the cross-folds of said record-ply. Passing the work-ply 22 downwardly over the cross-piece 40 instead of over the cross-bar 13 is desirable for another reason, where the plies of the 30 web are made of relatively thick paper. In such case, ridge-like formations at the folds 37 in the record-ply would often catch in groove-like formations of the work-web adjacent the cross-bar 13.

According to another form of this invention, illustrated in Figure 8, instead of feeding a unitary web from which the record-web is separated, a web 42 and a cross-folded continuous record-strip 43 are fed to the machine. One of the advantages claimed for this form of the invention is the provision of a more compact record-web and the consequent saving in the length thereof. It is assumed that bill-forms are used having a 45 heading 44, a billing space 45 upon which all the data is typed, and a lower portion or foot 46 upon which printed instructions regarding the disposing of the forms may appear. Often, only the typed items on the bill are required to appear on the record-strip, and, to this end, the record-strip is cross-folded in lengths corresponding to the length of the billing space of the form. In order to handle this class of work, however, a different procedure is followed in the operation 50 of the machine. In the first place the slitting knife is eliminated, and both the statement-web and the record-strip are threaded through the carbons and are then passed around the platen together with the interleaved carbons as a single pack, the record-strip 43 being led 55 behind the front table over the clamping member 24 in the manner described while the web 42 is passed over the table.

After typing each bill, the platen is rotated

to position the record-strip ready for the typing of the next form, that is to say, the cross-fold or crease 47 on the record-strip, which is wider than the statement-web, is run up past the printing line, as shown in Figures 12 and 16. Then, the web is straightened out, as shown in Figure 13, and the web is pulled forwardly to the gage 25 while the carbons are run backwardly to be presented to a fresh portion of the web and of the record-strip, the platen being subsequently lowered to normal position and the typed form severed in the regular manner against the knife 48.

In cases where the statement-web cross-folds are spaced a short distance apart, as at the end of each form, and the cross-folds of the record-web are even closer together, and the webs are very flexible, the refolding guide may be omitted. Referring again to Figure 8, it will be noted that the record-strip is delivered out of the machine over the entering strip. In this case, due to the shortness of the folds, it is possible to place the delivering receptacles 49 and 50 slightly out of alignment, the receiving receptacle 51 being located so that the middle portion thereof is in line with the turn in the web about the bar 13.

In order to identify the particular folds of the record-sheet, the record-sheet folds and the bill-forms may be numbered, the numbers being indicated generally by the numeral 52. This is an important feature, especially in the case where a separate record-web is inserted in the machine, as there is no place provided for the name identifying the particular transaction.

For clearness in the reading of the drawings, in some of the figures, the lines indicating the bill-forms, the headings and the footings thereof are indicated also by numerals 53, 54 and 55, respectively, each being shown in the several views where the web is shown.

When a long record-web is to be refolded into a tall work-pack or book according to the present invention, it is advantageous to have the refolding take place in a bin or box centrally disposed below the refolding guide to guard against the tall stack of cross-folds toppling over, which would prevent further refolding of the record-ply. In order that the record-web may refold properly into the bin, the latter should be positioned a distance below the refolding bar not less than the lengths of two cross-folds of said record-web.

Variations may be resorted to within the scope of the invention, and portions of the improvements may be used without others.

Having thus described my invention, I claim:

1. An equipment for typing plies of a composite web and producing a typed record-web in book-form to be readily accessible throughout its length, including the combi-

70

nation with a typewriter-carriage, of a stationary bin or receptacle to contain a main web and the record-web, forming together within said bin a single cross-folded web-
5 pack, means including a guide at the rear of the typewriter-carriage to conduct the composite web upwardly from said bin and forwardly to the typing instrumentalities, means at the delivery side of the platen for strip-
10 ping the typed record-web intact from the main plies of web and feeding said record-web rearwardly over the incoming main web, and a refolding organization including a bar in the rear of said incoming guide, over
15 which bar said record-web falls, and also including a second stationary receptacle into which the refolded book or pack fits in rear of the first-named bin, said second receptacle receiving the typed record-web as it falls and
20 refolds into a book.

2. In a web-manifolding typewriting machine, the combination with a revolute platen around which may be fed to typing position a multiple-ply transversely-folded
25 work-web including a record-web drawn from a work-pack at the rear of said machine, means for delivering solely the typed record-web rearwardly over the work-web in the rear of said platen, and a carriage-ex-
30 tension having two spaced cross-rods supported on the rear end of said carriage-exten-
sion, one of said cross-rods guiding the enter-
ing portion of said work-web forwardly to
35 said platen, of a refolding organization in-
cluding a guide for directing said record-
web to be cumulatively refolded into a work-
pack having side members disposed on either
40 side of said work-web whose front ends hook
over one of said cross-rods and behind the
other cross-rod, and an integral cross-piece
45 disposed a distance to the rear of the enter-
ing portion of said work-web for guiding
said record-web past said work-web without
binding the latter at said cross-rods, and to
said work-web.

3. In a manifolding typewriting machine having a carriage and a platen, around which
50 may be fed a multiple-ply work-web with in-
terleaved carbons, including a main web and a cross-folded record-web which is disposed next to the platen, said machine also includ-
ing a knife for severing the typed forms one
55 by one from the main web, and means for effecting relative stripping or shifting be-
tween the web and an interleaved inking de-
vice, the combination of means upon the car-
riage in advance of said knife for separating
60 the record-web from the main web, so as not
to be severed therewith, said separating
means including a table extending up from
the delivery side of the platen for supporting
65 the main web, said table separated from the

in whole condition to pass back thereunder, and means for guiding the unsevered record-
web rearwardly and out of the machine over
the incoming multiple-ply web, said rear-
ward guiding means including an outrigger
70 extending back far beyond the point where
the multiple-ply web feeds into the machine
to permit the record-web to dangle and upon
reaching the floor or other support to refold
75 to form a book, said outrigger being at a
height to accommodate the edgewise move-
ment of the upper portion of the dangling
web with the carriage, while the lower end is
stationary at the book.

4. In a typewriting machine having a
platen mounted on a carriage and a rear car-
riage traveling with said platen-carriage, the
combination with a web-guiding cross-bar
80 upon the rear extremity of said rear carriage,
of a pair of spaced side members hooked
over said cross-bar to be supported thereby,
and a cross-piece connecting the side mem-
bers in a position spaced beyond said cross-
bar.

5. In a typewriting machine having a
platen mounted on a carriage and a rear car-
riage traveling with said platen-carriage, the
combination with a web-guiding cross-bar
90 on the rear extremity of said rear car-
riage, of an outrigger in rear of said cross-
bar in position to straddle an ascending web
entering over said cross-bar toward said
platen, and having means to direct a return-
ing web-ply over and past said entering web,
and in position to permit said web-ply to fall
100 and form itself into a book upon a suitable
support.
